UNITED STATES PATENT OFFICE.

GEORGE NAISMITH, OF PITTSBURGH, PENNSYLVANIA.

BOILER SETTING.

Application filed March 16, 1922. Serial No. 544,165.

To all whom it may concern:

Be it known that I, GEORGE NAISMITH, a citizen of the United States, residing at Pittsburgh, in the county of Allegheny and 5 State of Pennsylvania, have invented certain new and useful Improvements in Boiler Settings, of which the following is a specification.

My invention relates to an improvement 10 in boiler setting, and more particularly to the construction of the enclosing walls of the furnace, with a view to providing for preheating of the air for the fuel. It has in view to preheat the incoming air, prior 15 to its admission to the furnace chamber for combustion with the fuel, as pulverized coal, by passing the air alternately through checkerwork heated by previously burned products of combustion, with means for effecting alternating reverse circulation of the 20 air, so as to utilize the waste heat to the best advantage.

The invention is illustrated in one preferred form, showing its application to a 25 standard double installation of water tube boiler of the vertical type, but is not restricted to any special installation or construction of the boiler elements themselves.

In the drawings, 30 Fig. 1 is a vertical sectional view through a boiler setting showing the circulation of the fuel and waste gases across through the furnace chamber and heating elements of a water tube boiler;

Fig. 2 is a horizontal section on the line 35 II—II of Fig. 1;

Fig. 3 is a transverse vertical section on the line III—III of Fig. 2.

The boiler construction is of typical form 40 utilizing upper steam supply drums 2 connected by banks of tubes 3, with lower mud drums 4 with an upper steam collecting drum 5 and the various usual connections and other parts not necessarily herein de-

scribed. It will be understood, also, that the invention is not necessarily dependent on the use of baffles, which may be utilized or not, as desired, to control or deflect the gases in circulation between the tubes 3, it being

understood that the heated air is to be introduced through openings in one inner wall and, after combustion with the fuel and circulation across through the tubes, to pass outwardly from the chamber, through corresponding openings in the opposite inner wall, in periodical alternating directions.

The combustion chamber *a* containing the boiler installation is enclosed within a surrounding wall structure comprising front and back walls 13—14, and companion inner 60 walls 16—17 respectively, with intervening outer circulation chambers containing the checkered refractory material 15, of well known construction, and inner downwardly extending air delivery chambers *c*. The 65 checker chambers, air chambers, and the combustion chamber are closed at the top, with a covering roof 6, and they communicate by bottom transverse conduits 18 through conduits or flues 19 between upper 70 and lower floor or bottom walls 20—21 respectively. Such bottom walls form, in effect, extensions of inner walls 16—17 and outer walls 13—14 to provide for the desired circulation outwardly from and inwardly towards the reversing valve *A* located in the lower middle portion of the 75 structure.

Said valve, which is of the usual Siemens construction, is located within a segregated 80 open ended chamber *b* within and between the inner boiler-supporting walls 22—22, above the floor wall 20 and below an enclosing upper partition 24. Chamber *b* communicates with the outside stack by an outlet conduit 25 for the waste gases, and air is supplied to the valve *A* from the atmosphere by the end openings 26 leading to the middle upper intake opening 27 of the valve, as is generally understood. 90

The reversible gate 28 is pivoted midway of the valve casing and by means of suitable operating connections is adapted to be thrown to alternating positions to direct incoming air from opening 27 through the end 95 circulating open channel 29 of the valve to the lower communicating conduits or channels 19 and 18, the latter leading upwardly to the checker chamber 15 at the receiving side of the furnace chamber. Fuel, in the 100 form of pulverized coal, is admitted through the series of openings 7 in the roof of the furnace, or in any other suitable manner, whereby to pass downwardly into the combustion chamber *a*. The incoming hot air 105 first passes from the top of the checker chambers containing the refractory material 15 downwardly through chamber *c* and then into the combustion chamber *a* through vertically and horizontally arranged series 110 of ports 8 in the inner wall 16.

At the other or outlet side of the chamber

a, the burnt gases pass inwardly through ports 8, upwardly by chamber c to the corresponding checker chamber 15, downwardly therethrough to channel or conduits 18-19, then upwardly through the other or closed circulating cavity 29 of the valve, and finally down through conduit 25 to the stack. It will be understood, of course, that the supply of powdered fuel through openings 7 alternates with the alternating valve control. Also, that the ports 8 provide for the circulation of the gases as just described, in alternating directions, as the valve is periodically reversed.

The operation of the invention will be readily understood from the foregoing description. Air is circulated in one direction or the other for a period of time, say twenty minutes, sufficient to absorb the heat from the previously heated checkerwork refractory material at one side of the chamber a, before issuing thereinto. At the same time, the outgoing waste gases of combustion pass by ports 8 and channel c into the checkerwork chamber at the opposite side, thereby heating the checkers for the next operation, on reversal of the valve.

By providing the inner walls 16-17 with the numerous ports 8, both vertically and transversely throughout substantially the entire height and width, the air is broken up and distributed by the checkerwork and such ports, so that it enters the combustion chamber in substantially equal volume and rate of flow at all portions of the chamber. The resulting effect is that, assuming the proper proportion and quality of fuel is being supplied, a very even and consistently unvarying heat is maintained across the entire area of the furnace chamber, with the resulting advantage of regular and economical heat transmission to the water in circulation through the headers or drums and their connecting tubes.

The advantages of the invention will be readily understood and appreciated by all those familiar with boiler practice, and it may be applied to different standard types or designs of boilers, by merely adapting the arrangement of the checker chambers and their inner walls and ports as to location, size, number, etc., to suit any particular installation. All such changes may be made by the designing engineer or builder, and are to be understood as within the scope of the following claims.

What I claim is:

1. In boiler construction, the combination with a centrally arranged water tube boiler, of a surrounding roof and wall structure providing an enclosing combustion and circulation chamber, each opposite end portion of the wall structure providing a main circulation chamber open at the bottom and top and containing refractory checkerwork and

having an inner wall provided with series of vertically and horizontally arranged circulation ports communicating inwardly with the combustion chamber, an intervening partition spaced therefrom terminating below the roof, forming the inner wall of the refractory chamber and providing circulation therefrom and thereto with the inner wall ports, and means providing circulation to and from the open bottom of each outermost refractory chamber.

2. In boiler construction, the combination with a centrally arranged water tube boiler, of a surrounding roof and wall structure providing an enclosing combustion and circulation chamber, each opposite end portion of the wall structure providing a main circulation chamber open at the bottom and top and containing refractory checkerwork and having an inner wall provided with series of vertically and horizontally arranged circulation ports communicating inwardly with the combustion chamber, an intervening partition spaced therefrom terminating below the roof, forming the inner wall of the refractory chamber and providing circulation therefrom and thereto with the inner wall ports, a middle supporting wall structure below the boiler providing an air supply chamber, and a reversible valve and casing therein providing communication between the bottom of each refractory chamber and with the air supply and exhaust respectively.

3. In boiler construction, the combination with a centrally arranged water tube boiler, of a surrounding roof and wall structure providing an enclosing combustion and circulation chamber, each opposite end portion of the wall structure providing a main circulation chamber open at the bottom and top and containing refractory checkerwork and having an inner wall provided with series of vertically and horizontally arranged circulation ports communicating inwardly with the combustion chamber, an intervening partition spaced therefrom terminating below the roof, forming the inner wall of the refractory chamber and providing circulation therefrom and thereto with the inner wall ports, a middle supporting wall structure below the boiler providing an air supply chamber, a reversible valve therein having a casting opening to the atmosphere and to an exhaust conduit respectively, and independent conduits connecting said casing with the base of each checkerwork chamber respectively whereby to effect alternating circulation therethrough.

4. In boiler construction, the combination with a water tube boiler, of a surrounding structure providing an enclosing combustion and circulation chamber and embodying opposite end walls each provided with an open bottom and top refractory chamber, a partition forming the inner wall of said refrac-

tory chamber spaced from the innermost wall providing a circulation space communicating with the upper end of the refractory chamber, series of vertically and laterally arranged ports through the innermost wall establishing circulation between said space and the combustion chamber at each end, a middle covered valve chamber serving as a support for the boiler, and a reversible valve therein communicating with the base of each refractory chamber, with the atmosphere, and with an exhaust conduit.

In testimony whereof I hereunto affix my signature.

GEORGE NAISMITH.
